UNITED STATES PATENT OFFICE

126,837

DESIGN FOR A STEMMED GOBLET OR SIMILAR ARTICLE

William P. Morrison, Mount Pleasant, Pa., assignor to Bryce Brothers Company, Mount Pleasant, Pa., a corporation of Pennsylvania

Application March 10, 1941, Serial No. 99,457

Term of patent 14 years

To all whom it may concern:

Be it known that I, William P. Morrison, a citizen of the United States, and residing at Mount Pleasant, in the county of Westmoreland and State of Pennsylvania, U. S. A., have invented a new, original, and ornamental Design for a Stemmed Goblet or Similar Article, of which the following is a specification, reference being had to the accompanying drawing, forming a part thereof, wherein:

Figure 1 is a view in elevation of a stemmed goblet, showing my new design; and

Figure 2 is a sectional view taken on line

II-II of Figure 1, looking in the direction of the arrows.

It is to be understood, however, that while I have illustrated the design of my invention as applied to a goblet, it is equally applicable to a complete line of stemmed glassware in addition to goblets.

I claim:

The ornamental design for a stemmed goblet or similar article, substantially as shown and described.

WILLIAM P. MORRISON.
